(57) **CLAIM**

We claim the ornamental design for a firearm suppressor cover, as shown and described.

DESCRIPTION

FIG. 1 is a perspective view of a firearm suppressor cover according to an illustrative embodiment;
 FIG. 2 is a front view of the firearm suppressor cover of FIG. 1;

FIG. 3 is a cross-sectional right side view of the firearm suppressor cover of FIG. 1 taken at 3-3; and,
 FIG. 4 is a perspective view showing a firearm suppressor mounted within the firearm suppressor cover of FIG. 1.
 The subject matter illustrated in dashed lines, and any surfaces of the design not shown, form no part of the claimed design.
